UNITED STATES PATENT OFFICE.

JOHN THOMAS McCONNELL, OF WICHITA, KANSAS, ASSIGNOR OF ONE-HALF TO JAMES H. NEWELL, OF WICHITA, KANSAS.

RAIL-CLAMP.

1,223,992.

Specification of Letters Patent. Patented Apr. 24, 1917.

Application filed December 27, 1916. Serial No. 138,091.

To all whom it may concern:

Be it known that I, JOHN THOMAS McCONNELL, a citizen of the United States, residing at Wichita, in the county of Sedgwick and State of Kansas, have invented certain new and useful Improvements in Rail-Clamps; and I do hereby declare the following to be a full, clear, and exact description of the invention, such as will enable others skilled in the art to which it appertains to make and use the same.

This invention relates to railway rail clamping devices, and has for its object the provision of a clamp that will accommodate ties of different widths, will admit of a rail being conveniently and expeditiously clamped, can be cheaply manufactured and will be durable and efficient in operation.

Other objects will appear and be better understood from that embodiment of my invention of which the following is a specification, reference being had to the accompanying drawings forming a part thereof, in which:

25 Figure 1 is a detail side view of one end of a railway tie, with a rail section thereon, and showing the improved clamping device in operative position.

Fig. 2 is a top plan view of Fig. 1.

30 Fig. 3 is a detail perspective view of one end of one section of the clamping device detached from operative position, and

Fig. 4 is a section taken on the line 4—4 of Fig. 2.

35 Referring to the drawings in detail, the letter A designates a railway tie, and B a rail section resting on the tie. The clamping device for the rail section is formed of sections, designated 1. The sections forming 40 the rail clamping device lie, respectively, on opposite sides of the tie and each includes a bar 2 that extends parallel with the tie and is located at one side of the tie and extends beneath the base flange of the rail B, as 45 shown more particularly in Figs. 1 and 2 of the drawings. Each bar 2 is provided with a pair of substantially L-shaped flanges 3, which overlie the upper side of the tie A, and are located, respectively, at 50 the opposite ends of the bar 2, and the respective flanges of each pair lie on opposite sides of the base flange of the rail B. The flanges 3 are disposed above the planes of the bars 2, and each flange has the short 55 arm thereof terminally secured to the upper

side of the adjacent end of the adjacent bar 2, and the long arm of the flange is extended at an acute angle to the short arm and has the other end thereof integrally secured to the upper side of the adjacent bar, as shown 60 more particularly in Fig. 3 of the drawings. The outer side of the long arm of each flange 3 is provided with a plurality of shoulders 6, arranged in echelon, as shown in Figs. 2 and 3, and are provided with openings 7, 65 that extend transversely through the shoulders and the long arm of the flange 3. The openings 7 in the long arms of the flanges on one bar 2 register with the openings in the long arms of the flanges on the other 70 bar 2, and the long arms of the flanges 3 on one bar 2 are adapted to be connected to the long arms of the flanges 3 on the other bar 2 by means of connecting rods 8 that are adapted to be received by any respective 75 openings in the opposed long arms of the flanges 3. When the fastening device is associated with a tie having a minimum width, the connecting rods 8 are received by the openings 7, which are located adjacent 80 the inner terminals of the long arms of the opposed flanges 3, as shown in Fig. 2. When the fastening device is to be mounted on a tie of greater width, the connecting rods 8 are received by certain other opposed 85 openings 7 that are located nearer the center of the opposed long arms of the flanges 3. Each of the connecting rods 8 has one end provided with a head 9, which engages the outer side of the long arm of one of the 90 opposed flanges 3, and the other end of the rod is threaded, and has a nut 10 turned thereon and adjusted against the outer side of the long arm of the other opposed flange. When the sections 1, of the clamping device, 95 have been positioned on a tie, the connecting rods 8 are inserted through certain of the opposed openings in the long arms of the opposed flanges, which will admit of the threaded ends of the rods being sufficiently exposed to accommodate the nuts 10. The nuts 10 are then turned on the rods 8 and adjusted against the adjacent long arms of the opposed flanges 3, so as to cause the 100 bars 2 of the sections 1 to tightly clamp the tie body A. The bars 2 of the respective clamping sections 1 are provided with pointed prongs formed integral with the inner surfaces of the rods, and which are adapted to be driven into the respective sides 110

of the tie body A. The outer sides of the bars 2 are provided with anvils, or lateral projections 12, which are located at points opposite the prongs 11, so as to provide surfaces for receiving the impact of a suitable tool during the operation of forcing the prongs into the tie, thereby preventing injury being done to the bars 2.

The inner ends of the long arms of the opposing flanges 3 are provided with inclined opening 13, and mounted within recesses in said openings are nuts 14, which have their bores registering with the openings 13. Screws 15 are received by the openings 13 and threadedly received by the bores of the nuts 14, and are adapted to have their lower ends adjusted against the base flange of the rail B, as shown in Figs. 1 and 2 of the drawings, so as to prevent rising or creeping of the rails.

It is evident that various changes might be resorted to in the construction, form and arrangement of the several parts without departing from the spirit and scope of the invention as claimed.

Having thus described my invention what I claim as new, is:

1. A rail clamp formed of a pair of clamping sections, each section consisting of a bar adapted to engage one side of a rail tie and to extend beneath the base flange of a rail, and a pair of L-shaped flanges carried by the bar and adapted to overlie the upper side of the tie and to lie, respectively, on opposite sides of the base flange of the rail, the said L-shaped flanges each having the long arms thereof provided with a plurality of openings, the flanges on one bar opposing the flanges on the other bar, rail-engaging means carried by the flanges, and rods connecting the opposed flanges to each other and adapted to be received by the openings in the long arms of the opposed flanges, for the purpose specified.

2. A rail clamp formed of a pair of sections, each section consisting of a bar adapted to engage one side of a rail tie, flanges carried by the bar and adapted to

overlie the upper side of the tie and to lie, respectively, on opposite sides of the base flange of a rail, the flanges on one bar opposing the flanges on the other bar, means for connecting the opposed flanges to each other, and rail-engaging means adjustably associated with the flanges.

3. A rail clamp formed of a pair of sections, each section including L-shaped flanges adapted to overlie the upper side of the rail tie, the flanges on one section opposing the flanges on the other section, and each flange having the outer side of the long arm thereof provided with a plurality of shoulders arranged in echelon, the said long arms having openings therein extending transversely through the arms and the shoulders, rods connecting the opposed flanges and adapted to be received by the openings in the long arms of the opposing flanges, and rail-engaging means carried by the long arms of the flanges.

4. A rail clamp formed of a pair of clamping sections, each section consisting of a bar adapted to engage one side of a rail tie and to extend beneath the base flange of a rail, means for connecting the bar to the tie, flanges carried by the bars and adapted to overlie the upper side of the rail tie, and rail-engaging means adjustably associated with the flanges.

5. A rail clamp formed of a pair of clamping sections, each section consisting of a bar adapted to engage one side of a rail tie and having rail tie-engaging prongs formed integral with the inner side thereof, means carried by the bars for engaging over the rail tie, rail-engaging means carried by the first-mentioned means, and lateral extensions formed on the outer sides of the bars and located at points opposite the prongs, for the purpose specified.

In testimony whereof I affix my signature in presence of two witnesses.

JOHN THOMAS McCONNELL.
